(57) **CLAIM**

The ornamental design for a pie cutter with lid, as shown and described.

DESCRIPTION

FIG. 1 is a top plan view of a pie cutter with lid showing my new design with a pie cutter pan and a lid separated for clarity; FIG. 2 is a bottom plan view thereof; FIG. 3 is a right side elevation view thereof, the opposite side being a mirror image of the shown; FIG. 4 is a front elevation view thereof, the opposite side being a mirror image of the shown; and, FIG. 5 is an isometric view thereof.
